UNITED STATES PATENT OFFICE.

WILLIAM G. BROWNE, OF YONKERS, NEW YORK, AND ROGER W. OLMSTED, OF SAN FRANCISCO, CALIFORNIA.

POSTER PANEL.

Application filed September 12, 1927. Serial No. 218,972.

This invention relates to metal structures of the nature of panels, and is of particular utility when embodied in a poster panel for advertising purpose.

5 An object of the invention is to provide a metal panel of very strong structure having a flat central body portion adapted to receive and display the poster, this portion being surrounded by a moulding formed 10 integrally with the members or sections of which the body portion is composed, in the preferred form of panel.

Preferably there are at least two of these body sections, each having a section of 15 moulding at its outer margin and in pursuance of another object of the invention, the inner margins of the body sections are formed with interlocking flanges, to permit ready assembly of the body sections to form 20 a medial seam, the interlocking arrangement of the flanges serving to limit the lateral spread of the composite body portion.

In combination with these body sections, so arranged, the invention provides for end 25 sections, of which one is preferably a base and the other a head, each of these end sections also comprising a section of moulding. The above, and other objects of the invention, are illustrated and described 30 fully in the accompanying drawings and specification and are pointed out in the claims.

In the drawings,

Fig. 1 is a view in front elevation of a 35 poster panel in the construction of which the invention has been embodied.

Fig. 2 is a rear elevation thereof.

Fig. 3 is a sectional view upon an enlarged scale, taken on the line 3—3 of Fig. 1.

40 Fig. 4 is a sectional view on the line 4—4 of Fig. 1.

Fig. 5 is a detail view in perspective, partly in section, taken at the corner of one of the body sections.

45 Fig. 6 is a similar detail view of a half of the head section.

Fig. 7 is a similar view of the base section.

Fig. 8 is a similar view of the upper and lower right hand corners of the panel.

50 Fig. 9 shows a corner brace.

In the illustrated embodiment the parts designated by the reference numerals 1 and 2 are body sections, connected at 3 by an interlocking seam, for which purpose 55 each of the body sections has its inner mar-

gin formed with a return flange, 4, these flanges preferably extending from top to bottom of the inner margins and serving when assembled to hold the body sections against lateral displacement.

60 Each body section preferably has a moulding 5 formed integrally with its outer margin and extended at the ends 6 to form a mitred corner portion.

To complete the panel two end sections 7 and 8 are provided, mitred at their ends 9 respectively to form corners co-operating with the mitred corner portions 6 of the body sections, and each end section has preferably an offset lip 10, adapted to slip 70 behind the contiguous ends of the body sections, the latter having diagonal lugs 11, (see Figs. 5 and 6), which overlap the adjacent end portions of the end sections as illustrated, and are welded or soldered 75 thereto, strengthening the corner joints. As a further means to strengthen the corners the invention provides for metal corner pieces 12, bent around the extreme corners and affording an ornamental finish.

80 Angle pieces 13, may also be provided, preferably welded to the rear of the structure, near the inner corners of the mitred joints. A brace 15 may also be welded to afford additional strength to the top section 85 when the latter is formed with a pediment and architrave as illustrated. The end sections may desirably have portions 16, bent over into position to engage with longitudinal flanges 17 formed along the rear edges 90 of the body section mouldings, to which the portions 16 may be welded, or otherwise secured.

When thus assembled, the end sections serve to hold the body sections at the extreme lateral position permitted by the interlocking medial seam, and the various corner pieces and angle reinforcements serve to maintain the parts in assembled position, the panel as a whole being a strong, 100 light, unitary structure, having a smooth, flat display portion to receive posters, which may be readily removed and replaced by others without injury to the panel.

105 We claim:

1. A metal poster panel comprising body sections having marginal flanges adapted to be assembled to form an interlocking seam, said body sections having other margins formed with integral mouldings with mi- 110

tered extensions; and end sections formed with integral moulded portions having mitred ends to form corners with the mitred corners of said body sections and with integral marginal lips offset to extend behind the ends of the body sections respectively, said end sections serving, when thus assembled, to hold said body sections in the extreme lateral position permitted by said interlocking seam, said panel comprising also corner members securing together the other contiguous mitred portions of said body and end sections.

2. A metal poster panel comprising body sections having marginal flanges adapted to be assembled to form an interlocking seam, said body sections having other margins formed with integral mouldings with mitred extensions; and end sections formed with integral moulded portions, having mitred ends to form corners with the mitred corners of said body sections, and with integral marginal lips offset to extend behind the ends of the body sections respectively, said end sections serving, when thus assembled, to hold said body sections in the extreme lateral position permitted by said interlocking seam, said panel comprising also corner members securing together the outer contiguous mitred portions of said body and end mouldings, said corner members comprising metal strips folded across the front of said corners and around the sides thereof.

3. A metal poster panel comprising body sections having marginal flanges adapted to be assembled to form an interlocking seam, said body sections having other margins formed with integral mouldings with mitred extensions; and end sections formed with integral moulded portions, having mitred ends to form corners with the mitred corners of said body sections, and with in-

tegral marginal lips offset to extend behind the ends of the body sections respectively, said end sections serving, when thus assembled, to hold said body sections in the extreme lateral position permitted by said interlocking seam, said panel comprising also corner members securing together the other contiguous mitred portions of said body and end mouldings, said corner members comprising metal strips folded across the front of said corners and around the sides thereof, and angle pieces secured to the rear of said mitred portions, across the inner portions of the mitred joints.

4. A metal poster panel comprising body sections having marginal flanges adapted to be assembled to form an interlocking seam, said body sections having other margins formed with integral mouldings with mitred extensions; and end sections formed with integral moulded portions, having mitred ends to form corners with the mitred corners of said body sections, and with integral marginal lips offset to extend behind the ends of the body section respectively, said end sections serving, when thus assembled, to hold said body sections in the extreme lateral position permitted by said interlocking seam, said panel comprising also corner members securing together the other contiguous mitred portions of said body and end mouldings, said corner members comprising metal strips folded across the front of said corners and around the sides thereof, and angle pieces secured to the rear of said mitred portions, across the inner portions of the mitred joints by welding.

In witness whereof, we have signed this specification.

WILLIAM G. BROWNE.
ROGER W. OLMSTED.
